Inventor;

Marie Elise von der Lindan

UNITED STATES PATENT OFFICE.

MARIE ELISE VON DER LINDEN, OF HOBOKEN, NEW JERSEY.

BUTTON.

SPECIFICATION forming part of Letters Patent No. 665,042, dated January 1, 1901.

Application filed May 25, 1898. Serial No. 681,711. (No model.)

To all whom it may concern:

Be it known that I, MARIE ELISE VON DER LINDEN, a citizen of the United States, residing at Hoboken, in the county of Hudson and 5 State of New Jersey, have invented a new and useful Improvement in Buttons, of which the following is a specification.

The object of my invention is to provide a button and eyelet therefor adapted to fasten 10 shoes and other articles composed of leather, rubber, and analogous material.

By my improvement the necessity of sewing the button in place is obviated, thereby saving time, labor, and expense, and in the 15 event of accidental breakage or damage thereto the button can be readily replaced by another.

The construction and arrangement of my improved button prevents it from working 20 loose or falling out when once properly inserted, and by reason of the form of the eyelet, with which the button is combined, the leather or other material is prevented from wearing or tearing.

25 In the accompanying drawings I have shown my improvement applied for fastening shoes.

Figure 1 is a side elevation of a portion of a shoe-upper before being fastened and showing the shank of one of the buttons in section 30 within an eyelet. Fig. 2 is a horizontal section through the eyelet and material forming the shoe-upper. Fig. 3 is a vertical section of the same. Fig. 4 is a perspective view of the button.

35 *a* is the outer leather portion of a shoe-upper, having buttonholes *b* and provided with an inner stripe *c* and an outside lining *d* in the usual manner.

e is a strip of thin leather or like material 40 arranged to cover the row of eyelets *f*. The above thicknesses of material are secured to

gether by rows of stitches *g* and *h*, the former being close to the eyelets. The eyelets *f* are formed with oblong openings and are rigidly secured in place to bind the outer layer *a* and 45 the strip *c* together.

The button comprises a head *i*, having a shank *j* and a cross-bar *m* in one piece, the latter forming arms *k* and *l*. The arm *k* is made approximately twice as long as the arm 50 *l* and is intended to occupy the lowermost position when in use. The length of the arm *l*, together with the thickness of the shank, will equal the distance of the oblong opening of the eyelet in order to insert the button in 55 place. To do this, the long arm *k* is first inserted through the eyelet horizontally and the button then moved laterally to the left until the shank reaches the end of the oblong opening, as shown at *n*, Fig. 1. The short arm 60 *z* can then be rocked through the opening and the arms given a quarter-turn into the vertical position shown dotted in Fig. 1. In this position gravity, aided by the strip *e*, serves to secure the button in place and prevent any 65 tendency to fall out. In the event of accidental breakage or wearing out of the button the shank can be readily removed and another button substituted.

I claim—

70 In combination a button containing a head, a shank and a cross-bar, the cross-bar forming arms, one on each side of the shank, one of which arms is approximately twice the length of the other; an eyelet having an elongated opening corresponding in length to that of the short arm thereto added the thickness of the shank; substantially as described.

75 MARIE ELISE VON DER LINDEN.
